UNITED STATES PATENT OFFICE.

WILLIAM W. ZICKLER, OF MULLAN, IDAHO.

MINER'S LAMP.

Application filed April 10, 1922. Serial No. 551,324.

To all whom it may concern:

Be it known that I, WILLIAM W. ZICKLER, a citizen of the United States, residing at Mullan, in Shoshone County and State of Idaho, have invented certain new and useful Improvements in Miners' Lamps, of which the following is a specification.

My present invention relates to improvements in miners' lamps, of that type which is supported on the hat worn by the miner. In many instances a hat with a brim is preferred by the miner, rather than a cap without a brim, because of the fact that the brim of the hat forms a shield to prevent dropping water or small particles of material from falling down within the clothing at the neck of the wearer. With this condition in view the invention is particularly adapted for use with hats having brims, although the lamp of the invention is applicable for use when the miner is wearing a cap.

The primary object of the invention is the provision of a support for the lamp that is readily adjustable to the size of the hat of the wearer, which will insure a head gear for the lamp that may be firmly seated on the hat, and which will permit removal and replacement of the head-gear after, its initial adjustment, without necessity for re-adjustment or change, thus facilitating greatly the use of the lamp.

With these objects in view the invention consists in certain novel combinations and arrangements of parts as will be hereinafter more particularly set forth and claimed.

In the accompanying drawings I have illustrated one complete example of the physical embodiment of my invention wherein the parts are combined and arranged according to the best mode I have thus far devised for the practical application of the principles of my invention.

Figure 1 is a view in side elevation of a hat equipped with the lamp and head gear, according to my invention.

Figure 2 is a perspective view of the head gear for supporting the lamp.

In order that the invention may readily be understood I have indicated a hat of the usual felt type as H and provided with a brim B in Figure 1. The complete head-gear or support, as seen in Figure 2 is built upon the rectangular shield or pad 1 which may be of stiff material that is durable and may also be somewhat resilient for adapting it to the curvature of the head and hat

of the wearer. In connection with the pad an annular band is used which constitutes sections 2 and 3 made of flexible material as leather or duck, and these sections are joined at the rear by a buckle 4 of usual type. As shown the band is adapted to be passed around the band portion of the hat just above the brim and the sections joined at the rear by the buckle. Each of the sections 2 and 3 is provided with an elastic portion as 5, 5, situated nearer the front of the band with relation to the rear buckle 4. The annular band, or its two sections 2 and 3, is secured at the lower end of the pad, as by rivets 6, and passes across the front face of the pad as indicated. In applying the head gear to the wearer, it will be apparent that the sectional band is passed around the hat while in position on the head, and the buckle 4 connected to insure a firm support of the band on the hat and head, with the elastic portions or inserts 5 under tension. Thus these elastic portions hold the band in close frictional contact with the hat. When the head gear is removed the elastic portions are slightly expanded to permit removal, then, when the head gear is then applied it is slipped over the crown of the hat and properly positioned. The buckle 4 after having first been adapted to proper relation is not again disturbed, as the elastic portions 5 permit ready removal and equally facile replacement of the head gear.

The vertically disposed pad or shield 1 is braced by means of a crown-band which comprises a fixed strap 7 extending across the top face of the pad and secured thereto by rivets 8, and the free ends of this fixed strap are connected to side straps 9 and 10 by buckles 11 and 12. At 13 the rear ends of the side straps are secured to the sectional band, and this latter band and the crown band thus form an openable head gear, the openable joint being provided by the use of the buckle 4 at the rear.

By means of the buckles 11 and 12 the crown band may be adjusted to the proper or required tension for holding the pad in either vertical position, or in a slightly inclined position to accommodate the lamp 14.

The lamp used may be of approved type as electric, or a carbide gas lamp, and is attached at its lower end within the spring arms 15 that form a clip and are secured at the front of the pad near its lower edge.

At its upper edge the pad is fashioned with a centrally located socket as 16 formed between the fixed strap 7 and the face of the pad. This socket is adapted to receive the 5 supporting hook 17 at the top and rear of the lamp. In Figure 1 it will be seen that the lamp is retained in position by the hooked connection at the top and the spring retaining clip or clamp 15 at the bottom, and 10 the lamp is further supported by resting on the brim B of the hat.

From the above description taken in connection with my drawings it will be apparent that I have devised the head-gear 15 for a miner's lamp which fulfills the requirements and purposes heretofore set forth.

Having thus fully described my invention what I claim as new and desire to secure by Letters Patent is—

The combination with a pad of a band having elastic portions therein and a rear detachable fastening device for the free ends of the band, a crown band comprising a strap fixed on the pad and formed with 25 a socket, side straps attached to the first mentioned band, detachable fastening devices connecting the ends of the fixed strap and the free ends of the side straps, and a clamp fixed to said pad having resilient retaining arms.

In testimony whereof I affix my signature.

WILLIAM W. ZICKLER.
